Primary Examiner—M. N. Pandozzi**Attorney, Agent, or Firm**—Kevin E. Flynn; Michael G. Johnston; Moore & Van Allen, PLLC**[57]****CLAIM**

The ornamental design for a cup with space for printed matter, as shown and described.

DESCRIPTION

FIG. 1 is a side elevational view of a cup with space for printed matter showing our new design, all sides being the same; and,

FIG. 2 is a bottom plan view thereof.

The broken line showing in FIG. 1 is for illustrative purposes only and forms no part of the claimed design.
